[57] CLAIM

The ornamental design for a tire, as shown and described.

DESCRIPTION

FIG. 1 is a perspective view of a tire for a vehicle wheel showing our new design, it being understood that the tread design is repeated throughout the circumference of the tire, the opposite side being the same as that shown;

FIG. 2 is a side elevational view thereof; and
FIG. 3 is a front elevational view thereof.

FIG. I

FIG. 2

FIG. 3
